UNITED STATES PATENT OFFICE.

FRANCIS W. CLOUGH, OF SPRINGFIELD, MASS., ASSIGNOR TO NELSON C. NEWELL, OF SAME PLACE, AND JOHN C. DICKINSON, OF NEW YORK, N. Y.

MACHINE FOR ATTACHING BUTTONS TO SALE-CARDS.

SPECIFICATION forming part of Letters Patent No. 224,583, dated February 17, 1880.

Application filed October 31, 1879.

To all whom it may concern:

Be it known that I, FRANCIS W. CLOUGH, a citizen of the United States, residing at Springfield, in the county of Hampden and State of Massachusetts, have invented new and useful Improvements in Machines for Attaching Buttons to Sale-Cards, of which the following is a specification.

My invention relates to that class of machines which are employed by button manufacturers for attaching buttons to sale-cards by passing a wire staple through the holes in the buttons and through the card to which they are to be attached, and then spreading or clinching the legs of the staple on the under side of the card; and it consists of devices for placing buttons on a button-card under two needles which pass through the holes in the button and pierce holes in the card under it; of devices which form and drive a wire staple through said button and card, following the holes pierced by said needles; of devices which clinch the legs of said staple under said card, and of card-feeding devices which move the button-card under said needles, so that the buttons are attached thereto in uniform parallel rows across said card, as will be herein-after specifically described, reference being had to the accompanying drawings, in which like figures and letters refer to like parts in the different figures.

Figure 1 is a front elevation of my machine. Figs. 2 and 3 are side elevations of the same. Fig. 4 is a view of the button-feed devices. Fig. 5 is a plan view of the button-feed arm in position over a button. Fig. 6 is a view of the button-card table and of the devices which move it under the needles. Fig. 7 is a view of the card-feeding devices. Fig. 8 is a view of the button-card feed-arm and its pivot-support. Fig. 9 is a longitudinal section of a portion of the button-card table, showing a piece of card thereon and the position of the feed-arm under it. Fig. 10 is a view of the presserfoot and bar, needles and needle-bar, and staple former and pusher in their assembled positions, and showing a portion of the main shaft and the cams, levers, and springs which

give movement to the presser-foot bar, the staple-pusher, and the staple-former. Fig. 11 is a vertical section of the lower end of the needle-bar, showing the positions of the staple former and pusher therein. Fig. 12 is a view, partly in section, of the lower end of the needle-bar and needles, the staple-former with a bent staple on it and its socket-block, the staple-pusher, and a portion of the wire-cutter with a piece of wire therein. Fig. 13 shows a finished staple. Fig. 14 is a side elevation of the wire-feeding devices, showing the manner in which they are operated by a cam on the main shaft and a lever, with the wire shown leading through the above-named feed devices into the wire-cutter, which is shown pivoted behind the needle-bar, the latter, with the staple pusher and former, being shown in their relative positions to the wire-cutter. Fig. 15 is a view of the needles, showing longitudinal grooves therein, in which a formed staple is shown in the act of being carried down between them by the staple-pusher. Fig. 16 is a transverse section (enlarged) of the needles and staple through the line xx , Fig. 15. Fig. 17 shows a piece of button-card, a staple, and a button between the staple-pusher on one side and the staple-fastening devices on the other, and the mechanism by which the latter devices are operated. Fig. 18 shows the construction, in detail, of the staple-spreader. Fig. 19 is a plan view of the button-cup and intermediate table between it and the button-card table. Fig. 20 is a side elevation, partly in section, of the lower end of the needle-bar, showing the groove in the side of the vertical passage therein leading into the groove in the needle.

The devices in this machine which operate in succession to accomplish the purpose of its construction are, almost without exception, each series of them, actuated independently by or from two principal shafts of the mechanism, and hence the construction, combination, and application of said devices, together with their relations to their main actuating devices, are much more clearly illustrated by having each series shown in detail, as they are herein, than

it would be were reference made in the description thereof principally to the drawings of a complete machine.

A novel feature of this machine is that the 5 downward movements of the parts which perforate the card for the staple, hold the button in place, and put the staple through the button and card are produced by devices whose actuating power is limited to such a degree of 10 force as is required for said operations, and any resistance that may be accidentally interposed between them and the work greater than that required for the latter does not tend to injure such parts of the machine.

15 The successive movements of the various parts of this machine in attaching buttons to a card and in causing the necessary change of position of said card relative to the needles and staple-fixing devices to cause the buttons 20 to be attached in rows across said card are as follows, viz: rotary motion of the button-cup; lifting of the staple-pusher; downward movement of the button-feeding arm; downward movement of the presser-foot bar; backward 25 movement of the staple-former; forward movement of the staple-former; upward movement of the presser-foot bar; forward movement of button-feed arm to carry the button under the needles simultaneously with the movement of 30 the button-card table forward or back; upward movement of the needles; forward movement of the wire-feed, pushing the end of the wire over the top of the staple-former; let-go and back movement of wire-feed; continued upward 35 movement of the staple-former into the staple-former socket to form the staple; downward movement of the presser-foot and backward movement of the staple-former; upward and backward movement of the button-feed 40 arm; downward movement of the needles, followed by the downward movement of the staple-pusher; upward movement of the staple-spreader, followed by the upward movement of the staple-former; downward movement of 45 the staple-fastener and spreader, and at the end of each row of buttons across the card.

Operation of the button-card feed to move the card longitudinally.—The operative parts of this machine are constructed, combined, and arranged 50 to operate together to affix buttons to sale-cards in rows upon said cards. The operator is only required to insert a line of staple-wire into the wire-feed, place a button-card on the machine, and to place buttons, one at 55 a time, upon the button-cup, when the machine will operate automatically to place said buttons on the card, make a staple, and with it to fasten each button upon the card independent of the others, placing them in rows across the 60 card in the usual order.

A frame, A, is constructed of suitable form and strength to support the shaft-standards 1 2 3 4 and bearings 6, 7, 8, 9, and 10 and the needle-bar and presser-foot-bar frame 11. Arranged to run in said standards and bearings are the principal shafts B and C and secondary shafts D E H.

B is the main shaft, on one end of which is shown a hand-crank. In an operative machine an ordinary belt-pulley is applied in place of 70 said crank.

Shaft B carries on its opposite end a crank, f, connected by a connecting-rod, d', with a pawl-lever, c⁸, arranged to oscillate on shaft C, and having pivoted on one side of it a pawl, 75 d⁴, with a spring, i¹¹, arranged to bear upon it. Shaft B carries also upon it a pulley, b, driving, by a belt, as shown, a pulley, b', on shaft D, hanging transversely under frame A, and also eight cams—viz., a, a', a², a³, a⁴, a⁵, a⁶, 80 and a⁷.

Shaft C carries upon it the pawl-lever c⁸, above mentioned, and has fixed to it a ratchet-wheel, d³, provided with teeth, as shown, of irregular circumferential length, a cam, a⁸, 85 and grooved crank-plate f⁴. The centrally-located frame 11 on the top of frame A, which supports the needle-bar and presser-foot bar and their immediately-connected devices, is perforated transversely, and shaft B, bearing 90 the aforesaid cams, passes through said frame. Frame 11 thus provides pivot-bearings for certain levers among others, which reach from back of shaft B forward and over cams on said shaft to operate certain devices, as will 95 be hereinafter more fully explained.

The construction and application of various parts of the machine, both in respect to their separate and combined action in performing the above-mentioned successive operations to 100 affix buttons to a card, are as follows, viz.: The rotary motion of the button-cup 19, into which the buttons are placed one by one by the operator, causes the button to be revolved in a horizontal plane under the end of a feed-lever, 20, in which are pins 21, arranged to project into the holes in the button when the latter, in its revolutions, brings said holes under said pins. The position of the button relative to said lever is seen in Fig. 5. Said 105 button-cup is made concave, as shown in Fig. 4, and in that figure are shown the devices connected therewith.

A shaft is supported under frame A, on each end of which is a pulley, b' b², and said shaft 115 is driven, as shown, by a belt from shaft B. Pulley b² drives, by a belt shown in Figs. 2, 3, and 4, a vertical shaft, D, running on a pulley, b³, on said shaft, which shaft is stepped in a support, 8, and has a bearing in frame A. On 120 the top of said shaft D is located the button-cup, partly surrounded by a low fixed rim rising above its upper surface, which is open on one side to allow the button to pass off from the cup.

The lifting of the staple-pusher o⁴ is produced by the revolution of cam a⁴ on shaft B, under a lever, c⁶, which is pivoted on frame 11, back of said shaft, the forward end of said lever being arranged to engage in a notch on 130 the side of said staple-pusher. Said cam is so formed as to allow said pusher to drop suddenly from its highest elevation.

The downward movement of the button-feed-

ing arm 20, to cause pins 21 to more surely engage in the holes in the button, as aforesaid, is produced by a spring, i , on vertical shaft H, which carries said arm on its upper end. Said shaft H is supported in frame A and in support 8 thereon, and its lower end is stepped in the end of lever c' .

The button-feeding arm is made flexible, so that it may not press too forcibly upon a button that may be of unusual thickness. The shaft H has a vertical and reciprocating rotary motion. The first is given to it by said lever c' , which is pivoted under frame A on support 9, and its end opposite to shaft H is arranged to engage with the lower end of a cam-post, e, which extends upward from said lever to and under a cam, a, on shaft B, so that the rotation of said shaft depresses said post and causes lever c' to lift shaft H, compressing 20 spring i between frame A and a crank, f^3 , on said shaft. Thus when cam a allows post e to rise up spring i draws shaft H and arm 20 down.

The downward movement of the presser-foot bar is effected by the action of spring i^4 thereon, as shown in Figs. 1, 2, and 10. Said presser-foot bar is slotted vertically, as shown, and secured against the side of frame 11 by pins which pass through said slots into said frame. On the bottom end of said bar is secured the presser-foot o' , consisting of two metallic rods descending vertically side by side, but separated from each other and having their lower ends bent at right angles over the button-card table. Before the said bar moves down, carrying said presser-foot, the button has, by arm 20, been placed on the card under said foot, and the latter descends and holds it, while other devices, as will be hereinafter described, fasten on the button.

The forward movement of the staple-former o^3 in the needle-bar o^2 presupposes the presence over said former of a piece of wire to form a staple from, and the operation of the devices 45 which place said wire there will be described farther on, and immediately following will be described those which operate to move the staple-former forward.

In Figs. 1, 10, 12, and 14 are shown the end 50 of the staple-former o^3 , over which the piece of wire which forms the staple is bent as said former rises up into a socket in block 30 on frame 11.

In Fig. 11 is shown the lower end of the 55 needle-bar in vertical section, showing the manner of hanging said staple-former therein, its general form, and a spring, o^6 , which operates to throw the former forward.

On the front side of frame 11 is pivoted, as 60 seen in Figs. 1, 2, 3, and 10, an elbow-lever, o^7 , in which is set a pin, o^{10} , extending back by the side of the needle-bar. Said pin o^{10} is in contact with the edge of the long vertical arm (see Fig. 11) of the staple-former above its pivot-point, for spring o^6 presses it out to that position when unobstructed by the posi-

tion of said pin o^{10} , which has a movement to and from the side of the needle-bar, as will be hereinafter described.

The presser-foot bar, whose downward movement has just been described, has in its front edge a pin, o^8 , and in descending said pin strikes the horizontal arm of lever o^7 , causing its vertical arm to carry pin o^{10} against the outer edge of the said arm of the staple-former, 75 and causing the latter to retire within the needle-bar.

Immediately that the presser-foot bar begins to rise, as hereinafter described, pin o^{10} releases its pressure upon the arm of the staple-former, letting spring o^6 operate to throw the 80 staple-former forward.

The presser-foot bar is lifted up by the action of a lever, c^4 , pivoted thereto and onto the side of frame 11, and whose opposite end 85 extends out under a cam, a^2 , on shaft B, which, revolving against said lever, operates to raise said bar, and at a certain point in its revolution to free it, letting spring i^4 press said bar down, as above set forth.

The presser-foot having been lifted from the button-card the forward movement of the button-card feed-arm takes place as follows: As heretofore mentioned, a crank, f^3 , is attached to the shaft H. Pivoted to said crank is one end of a connecting-rod, d^2 , and the other end of said rod is pivoted to the lower end of a vertical lever, c , Figs. 1 2 4, which is pivoted to the side of frame 11, and its upper end extends up back of a cam, a' , on shaft B, which, 95 revolving, operates said lever to swing the button-feed arm forward.

The movement of the button-card table 14 forward or back, which occurs simultaneously with the forward movement of arm 20, causes 100 the spot on the card where the next button is to be fixed to be brought under the needles. Said table lies on the top of frame A, across it, and is arranged thereon in a fixed position transversely by proper guides; but it has an 105 intermittent longitudinal movement backward and forward successively. The extent of said intermittent movements can be varied as may be required to correspond with the size of the buttons to be affixed to the card. Said table 110 has arranged upon its face four card-guides, 15, two on each side, which are adjustable transversely in grooves cut across the table, as shown in Fig. 6. On the face of said table, 115 as seen in the same figure, a series of graduation-marks, 16, is cut on the border of one of the guide-grooves. Thus when the machine is adjusted to a certain-sized card the longitudinal center line of the latter, together with said graduation-marks, help to get the card 120 in proper position on the table, when the said guides 15 can be adjusted to the edge of the card by means of the screws which secure them in the grooves. An opening through said table, nearly across it, under the needles, 125 is made, as shown, to allow the operation of staple-fixing devices directly under the

130

card, and a second opening therein, larger than the first-named one, between the latter-named one and the said graduation-marks, as seen in Fig. 6, provides for the free approach to the under side of the card of devices to feed said card longitudinally on the table, as will be hereinafter described. Over the said larger opening in the table is secured a flexible metallic plate, 17, whose ends reach over the edges of said opening and are slightly deflected toward the center, so that when the card slides between said plate and the table the plate will exert a slight frictional resistance to the movement of the card. Said plate 17 serves also to hold the card against the upward pressure of the feed devices, which operate under it. A steady-arm, 23, is secured to the under side of said table and extends back in frame A, for the purpose of causing the table to move on the frame without tipping or binding.

On the rear edge of said table is fixed a post, 24, to which is pivoted the end of a connecting-rod, d , the opposite end of which has a crank-pin box, h , fitted to it, so that it may have a longitudinal movement in a rectangular opening in said rod without moving the rod, as seen in Fig. 2. Through portions of said rod d , at each end of said opening, are arranged adjusting-screws h' and h'' , for the purpose of giving to said crank-pin box such a degree of movement in said rectangular opening as may be required for the purpose hereinafter described. Said crank-pin box h is connected to a properly-fitted block behind it, which is fitted adjustably to a dovetail groove across the face of a crank-plate, f^4 , secured to shaft C, so that by moving said block in the groove in said crank-plate the length of stroke given thereby to connecting-rod d may be varied at pleasure. On shaft C is also secured a ratchet-wheel, d^3 , having cut around its periphery teeth of irregular circumferential length, as seen in Figs. 2, 3, and 6, and by the side of said ratchet-wheel upon said shaft C is placed a pawl-lever, arranged, as hereinbefore described, to operate a pawl, d^4 , upon said ratchet-wheel.

The successive intermittent backward and forward movements of table 14 are produced as follows, viz: As hereinbefore explained, shaft C, to which is secured the crank-plate f^4 , is revolved intermittently by the action of pawl-lever c^6 and pawl d^4 upon ratchet-wheel d^3 . In order that the buttons may be set at regular distances apart in the rows across the card it is necessary that the movements of the table 14 under the needles be of equal length. It is obvious that such would not be the case if each movement of pawl d^4 caused the same degree of rotation in ratchet-wheel d^3 , for the crank-pin h in crank-plate f^4 does not at all points in its line of rotation impart to connecting-rod d a degree of horizontal movement equal to its degree of rotation. Therefore, since the segmental movement of the

pawl is regular, the length of the teeth around the periphery of the ratchet-wheel is irregular, to compensate for the above-named irregular movements of the crank-pin h . Thus it will be observed that when the crank-block groove in said plate has been brought around and left by the ratchet-wheel in a vertical position, or nearly so, the next movement of the pawl will be against the base of a short tooth, and the next one will be against the base of a long one, and so on. Thus the rotation of said crank-plate is caused to move the table 14 regularly under the needles.

The construction of the end of connecting-rod d to allow the crank-pin box to move freely in the rectangular opening therein for a certain distance is for the purpose of causing table 14 to rest an instant after each row of buttons has been set, to allow the card-feeding devices to move the card upon the table to bring the line for the next row of buttons under the needles. This rest takes place as the crank-pin is passing over nearly a horizontal line across the face of the crank-plate. A table, 18, partly surrounding the button-cup 19, is arranged between the latter and table 14, and extending over onto it, upon which the buttons are carried by arm 20 on their way to their place on the card under the needles.

The needle-bar o^2 is raised up by the action of cam a^6 on shaft B, upon the under side of lever c^7 , one end of which is pivoted to the side of frame 11, and its opposite end is made to engage with a pin in the side of said needle-bar, as seen in Fig. 3.

The wire from which the staples are made is drawn from any convenient reel near the machine through a tension-block and lubricator, 12, Fig. 3, which is located in the rear of the wire-feeding devices. Said tension-block is made concave on its top side, to form a receptacle for some suitable lubricant for the wire, and secured upon said block is a flat spring, 13, arranged to cover the top of it and permit the wire to be drawn under it and in contact with said lubricant. The end of the wire r^4 is drawn through said block and between the parts r and r' at the bottom of the groove in the latter, Fig. 14, and inserted into a wire passage in the wire-cutter o^{12} , as seen in the same figure.

After having placed the wire, as above described, in the wire-feeding devices, they operate as follows to feed the wire forward so that its end will pass through said wire-cutter and across the top of the staple-former before the latter is lifted up, as hereinbefore described, into the staple-former socket:

The wire-feeding devices are located on the side of frame 11, behind standard 2 and under shaft B, and between two parallel guides, r^3 , Fig. 14; and they consist of a widely-grooved piece, r , having beneath its upper side, as shown in said figure, a downwardly-projecting tongue; of a piece, r' , adjusted to slide and to have a vertical and longitudinal mo-

tion in the groove in piece r , and independent of the latter, and provided with a groove on its upper side, into which the tongue or piece r fits; of two parallel bars, r^2 , pivoted to the sides of the pieces r and r' ; of a friction-spring, r^3 , arranged to bear against the side of piece r , and there retained by a screw, as seen, which passes through a slotted passage in said piece into the frame 11; of a lever, c^5 , pivoted to frame 11 centrally, with its lower forked end engaging with a pin in the side of piece r' and its upper end held against a cam, a^3 , on shaft B by a spring, i^7 .

The position of the above-named parts, as seen in Fig. 14, is that in which they are found before they make their forward movement to feed the wire, and the feeding of said wire is effected by the revolution of cam a^3 against lever c^5 , throwing back its upper end and swinging its lower end forward, carrying with it piece r' , and the immediate effect upon the latter is to cause it to lift up, as well as to move forward, by reason of the swinging up of the two bars r^2 toward a vertical position, carrying the bottom of its groove against the bottom edge of the tongue on piece r , and grasping the wire therebetween. As soon as piece r' comes to a bearing against the wire, piece r slides, with the former, between guides r^3 , drawing the wire through box 12 and pushing it through the wire-cutter o^{12} over the staple-former o^3 .

The aforesaid wire-feed operations are immediately followed by the swinging of the wire-cutter o^{12} on its pivot, carrying the mouth of the wire-passage in its end next to the edge of block 30, Fig. 14, up by the edge of said block, thus cutting off that portion of the wire which extends out over the wire former. The wire-cutter is operated to cut off the wire, as above described, by the upward motion of the pin 35, fixed in the needle-bar, against the under side of the curved arm of the wire-cutter. A spring, 36, acts upon the wire-cutter to throw its cutting-edge down.

The wire-feeding devices retire and take a position preparatory to another forward movement as soon as cam a^3 releases lever c^5 by the action of spring i^7 upon said lever.

50 A socket is formed in that portion of block 30, Figs. 12 and 14, which is directly over the staple-former o^3 , and in Fig. 12 is shown said block with its front portion cut away, and showing said former up above the bottom edge 55 of said block. Thus, after a piece of wire, as aforesaid, has been cut off simultaneously with the movement of the staple-former up to the entrance of said socket, the central portion of the wire across said former is carried upward 60 into the socket, and the ends of the wire bend downward between the sides of the former and the socket, thus forming a staple, as seen in Figs. 12, 13, and 15.

The above-named operations are followed 65 by the downward movement of the presser-foot, the backward movement of the staple-

former, and the upward and backward movement of the button-feed arm 20, as already described.

The last-named movements are immediately 70 followed by the downward movement of the needle-bar through the action of spring i^5 on lever c^1 , passing the needles through the buttons and through the card, followed by the downward movement of the staple-pusher o^4 . 75

The needles o^5 are set one on each side of an opening down through the horizontally-projecting end of the needle-bar o^2 , as seen in Figs. 14 and 12. Said needles, two in number, have a groove cut in each one of them longitudinally, and the sides of the above-named opening in the needle-bar are grooved to correspond with the groove in each needle, and the latter are so set in the bottom end of the needle-bar that the said grooves in the sides 85 of the opening in the needle-bar lead into those in the needles, as shown in Fig. 20.

In Fig. 12 is shown a staple formed in the staple-socket, and, just above the staple, the lower end of the staple-pusher. The legs of 90 the staple, as seen in said figure, are formed in the said grooves in the socket, and upon the retirement of the staple-former, as aforesaid, from under the staple the staple-pusher drives the staple down, guided by the grooves 95 in the needles, through the button and through the card, as seen in Fig. 17. The staple-pusher o^4 is thrown down by the action of spring i^8 on the top of lever c^6 , as already partially described. At this stage of operations the 100 staple is found driven through the button and the card, and before the staple-fastening devices act the points of the needles rise slightly out of their way by the action of cam a^6 on shaft B upon lever c^7 , when they remain momentarily 105 stationary, and the staple-pusher holds down the staple while the said fastening devices act.

The staple-fastening devices are shown in detail in Figs. 17 and 18. They are operated by the action of a cam, a^5 , on shaft B to drive 110 down a camp-post, e' , working vertically in frame A thereunder, the bottom end of which is pivoted to one end of a lever, c^2 , which is pivoted upon support 10 under said frame, as seen in Fig. 3. The deflection of lever c^2 , to 115 which cam-post e' is pivoted, swings the opposite end of said lever up against the bottom of a hollow post, s' , which is arranged to move vertically in a guide-box, s , up toward the under side of the button-card 45, as seen in Fig. 17. 120

The upper end of post s' is bored out, and has fitted therein, as seen in Fig. 18, a staple-spreading pin, s^2 , which rests in said post s' upon a spring, i^2 . The side of post s' is perforated, so as to permit of passing a steady-pin, s^3 , through it into pin s^2 , to prevent the latter from turning around in post s' , but allowing it to have a free vertical movement.

The above-described devices operate to fasten the staple under the button-card as follows: As soon as the staple has been driven through the button and card, as above de-

scribed, the post s' is, by devices already named, moved upward. The end of the staple-spreading pin s^2 , beveled off on two sides, as shown, projects up above the end of post s' , held there by the spring i^2 under it. As post s' moves upward pin s^2 strikes its beveled sides against the legs of the staple, spreading them apart, as shown in Fig. 17. The spring i^2 is made of the requisite strength to hold pin s^2 up for this purpose, but not too great to prevent the card, with which pin s^2 immediately comes in contact, from crowding it down into post s' , and thus the end of the latter is brought up against the partially-spread legs of the staple, pushing them up against the under side of the card and completing the staple-fastening.

A spring, i^5 , is arranged to throw down post s' as soon as cam a^7 frees the end of cam-post e' .

The button-card is placed upon table 14 after the latter has been adjusted for its reception, as hereinbefore described, by sliding it between guides 15 thereon, under plate 17, and under the needles and presser-foot. The table is set so as to have its longitudinal movements on frame A commence at the end of a button-row on a card, and the latter is entered upon the table so that the needles will begin to operate on the first row next to the end.

After the before-mentioned devices have operated to fix a row of buttons across the card, the latter is caused to slide along on the table far enough to cause the next row of buttons to be set at a proper distance from the former one by the operation of the devices illustrated in Figs. 7, 8, and 9.

An elbow-lever, c^9 , is hung on support 9, which runs transversely across the under side of frame A, under table 14, so that the end of its vertical arm reaches up toward the under side of the button-card within the larger opening in said table hereinbefore mentioned, as seen in Fig. 17. Said elbow-lever is pivoted in support 9, as seen, so that it can rock on its pivot and have a longitudinal motion on support 9 and under table 14.

At right angles to the long arm of lever c^9 and under it, as shown in Figs. 3 and 7, is hung on support 7 and on frame A a rock-shaft, E, having upon it an upwardly-projecting arm, c^{10} , slotted at the top, as shown, and arranged to engage with a pin, c^{11} , projecting from the side of arm c^9 .

Secured also to shaft E is a horizontally-projecting arm, f^2 , to the end of which is pivoted the lower end of a vertically-operating cam-post, e^2 , which is driven downward by a cam, a^7 , on shaft B. A properly-arranged spring throws up the end of arm f^2 when post e^2 is freed from the action of cam a^7 .

Arranged to lift up under the end of lever c^9 , as seen in Fig. 7, is a lever, c^3 , pivoted on frame A and running back under a two-pointed cam, a^8 , on shaft C, and under lever c^3 is arranged a spring, i^{10} , as shown.

The above-described devices operate together to feed the button-card along on table 14 as follows: Cam a^8 is arranged to operate once every half-revolution of shaft C—that is to say, just before the commencement of a new row of buttons—to depress the end of lever c^3 and lift up, by its opposite end, the vertical arm of feed-arm c^9 against the under side of the button-card, and hold it there for an instant, while cam a^7 presses post e^2 down, turning rock-shaft E, and causing arm c^{10} thereon to move feed-arm c^9 longitudinally under the table, and carry with it the button-card, which is pressed between the under side of plate 17 on table 14 and the face of the roughened end of the vertical arm of the feed-lever c^9 . Immediately that the card has been thus moved the feed parts are disengaged from it, as above mentioned.

What I claim as my invention is—

1. In a machine for attaching buttons to sale-cards, the button-cup surrounded by a border projecting above its face and open on one side, as shown, and arranged to hold and revolve a button, in combination with the feed-arm adapted to carry the button from said cup onto a button-card, substantially as and for the purpose set forth.

2. The flexible button-feed arm provided with pins to enter the holes in a button, and arranged to have a vertical and a reciprocating rotary motion, substantially as and for the purpose described.

3. The combination, with shaft H and the button-feed arm 20, of spring i , lever c' , cam-post e , and cam a , substantially as and for the purpose set forth.

4. The combination of the table 18 and the table 14, substantially as and for the purpose set forth.

5. The table 14, having openings therein, as shown, and provided with transversely-adjustable guides 15, and having the graduation-marks 16 across its face, substantially as and for the purpose set forth.

6. The plate 17, secured upon table 14, and adapted to bear slightly upon the button-card as the latter passes under it, in combination with said table, substantially as and for the purpose described.

7. The combination, with table 14, of the steady-arm 23, secured thereto and extending longitudinally in frame A, substantially as and for the purpose set forth.

8. In combination, the crank-plate f^4 , adapted to revolve intermittently and with varying degrees of rotation and to move table 14 in opposite directions, the connecting-rod d , and said table 14, substantially as and for the purpose set forth.

9. The crank-plate f^4 , to carry the crank-pin h at different distances from its center, in combination with the connecting-rod d and the table 14, substantially as and for the purpose described.

10. The connecting-rod d , provided with a

- rectangular opening to permit the crank-pin box h to move longitudinally therein, and with the adjusting-screws h' h^2 , substantially as and for the purpose set forth. 70
- 5 11. The combination, with the crank-plate f^4 , of the ratchet-wheel d^3 , having teeth of irregular circumferential length cut around its periphery, substantially as and for the purpose set forth. 75
- 10 12. The combination, with the ratchet-wheel d^3 , having teeth of irregular circumferential length cut around its periphery, of the pawl-lever c^8 , provided with pawl d^4 , and arranged to oscillate with regular movements by the 15 side of said ratchet-wheel, substantially as and for the purpose described. 80
13. The presser-foot adapted to hold the button on the card while the button-feed arm rises and moves away from it, combined with the 20 staple-spreader and staple-fastener, and adapted to hold the button while the latter completes the fastening thereof upon the card, substantially as set forth and shown. 85
14. The combination, in a machine for attaching buttons to sale-cards, of the mechanism, substantially as shown, for lifting the presser-foot bar and presser-foot up from the card, and of a spring to press it down, substantially as and for the purpose set forth. 90
- 15 15. In combination, the needle-bar o^2 , adapted to be lifted by mechanism substantially as shown, and to be pressed downward by a spring, and the two needles to pierce the button-card, substantially as and for the purpose set forth. 95
16. The combination of the needle-bar, the staple-former to bend the staple and the staple-former socket, substantially as and for the purpose set forth. 100
17. The combination, with the needle-bar, of the staple-former adapted to operate in the needle-bar under the staple-wire and to recede from under the staple after the latter has been formed, substantially as and for the purpose set forth. 105
18. The combination, with the staple-former o^3 , of the spring o^6 , the elbow-lever o^7 , and the presser-foot bar o , substantially as and for the purpose set forth. 110
19. The needle-bar o^2 , provided at its lower end with a vertical passage, as shown, having grooves on two sides thereof to guide the staple on its downward passage, and having two longitudinally-grooved needles fixed in 155 said needle-bar and adapted to receive the staple between their grooved sides as it makes its exit from said grooved passage, substantially as and for the purpose set forth. 115
20. In combination with the needle-bar provided with the vertical passage having grooves on two sides thereof and two longitudinally-grooved needles located below said passage, the staple-pusher o^4 , substantially as and for the purpose described. 120
21. The combination, with the staple-pusher o^4 , of the mechanism, substantially as shown, for lifting it up from the button, and of a spring for moving it down against the staple, substantially as and for the purpose set forth. 125
22. The wire-cutter, arranged with a wire-passage through it, as shown, and to cut off the staple-wire, combined with the staple-former adapted to carry said cut wire to a bending-socket, substantially as and for the purpose described. 130
23. The wire-cutter pivoted to frame 11, and arranged to be operated by the upward movement of the needle-bar and by spring 36, substantially as and for the purpose set forth. 135
24. The combination, with the wire-cutter pivoted to frame 11, and provided with a wire-passage through it, of the needle-bar and of the block 30, to co-operate with said wire-cutter to cut off the staple-wire, substantially as set forth. 140
25. The combination, with the wire-cutter arranged to receive and cut off the wire, of the horizontally-operating wire-feeding blocks r and r' , to gripe and push the wire along, substantially as and for the purpose set forth. 145
26. In combination with the tongued feed-block r and the grooved feed-block r' , arranged between the guide-strips r^3 , and provided with the parallel straps r^2 , the lever c^6 , cam a^3 , and spring i^7 , substantially as and for the purpose set forth. 150
27. In combination with the feed-blocks r and r' , the spring i^9 , substantially as and for the purpose set forth. 155
28. The tension and lubricating block 12, located in the rear of the wire-feeding devices and provided with a spring-cover, 13, substantially as and for the purpose described. 160
29. In combination, the staple-spreader, to rise toward the under side of the card between the legs of the staple, and the staple-fastener to follow the staple-spreader, to carry the legs of the staple against the under side of the card, substantially as and for the purpose set forth. 165
30. The combination, with the staple-fastener s^1 , of the staple-spreader s^2 , spring i^2 , and pin s^3 , substantially as and for the purpose described. 170
31. The combination, with the staple-fastener, of the lever c^2 , post e' , cam a^5 , and spring i' , substantially as and for the purpose set forth. 175
32. In combination, the presser-foot and the staple-pusher, to hold the button and the staple against the top of the card, and the staple-spreader and staple-fastener, to move up against the under side of the card beneath the button, substantially as and for the purpose set forth. 180
33. The combination, with the button-card feed-arm, of the oscillating arm c^{10} and the lever c^3 , whereby a simultaneous upward and longitudinal motion is imparted to said feed-arm, substantially as and for the purpose set forth. 185
34. The plate 17, located on table 14, over 190

the button-card, and arranged to co-operate with the button-card feed-arm to slide the card on said table, substantially as set forth.

35. The combination, with the button-card feed-arm, of the rock-shaft E, provided with the arms c^1 and f^2 , the cam-post e^2 , cam a^7 , and spring i^3 , substantially as and for the purpose set forth.

36. The combination, with the button-card feed-arm, of the lever o^3 and cam a^8 , substantially as and for the purpose set forth.

37. The combination, with the needle-bar, of the mechanism, substantially as shown, adapted to lift the needles away from the button-card while the staple-pusher holds the staple against the button and while the staple-fastening devices are pressing up against the under side of the said card, substantially as and for the purpose set forth.

38. The combination, in a machine for attaching buttons to sale-cards, of the button-

cup to receive and revolve the button, of the button-feed arm to carry the button from said cup onto the card, of mechanism to form a staple from wire, of the grooved needles to pierce the card and to form guides to direct said staple through said card, of the staple-pusher to drive down the staple between the needles, and of the staple-spreader and staple-fastener, substantially as set forth.

39. The combination, in a machine for attaching buttons to sale-cards, of the table to hold and carry the card transversely between the button-attaching devices and of the feed-arm to carry the card longitudinally between the button-attaching devices, substantially as set forth.
